ELECTRICAL TERMINAL ASSEMBLY

Charles S. Milliken, Pasadena, Melvin B. Bosworth, Glendale, and Warren E. Gray, Van Nuys, Calif., assignors to Lockheed Aircraft Corporation, Burbank, Calif.

Application December 20, 1957, Serial No. 48,976

Term of patent 14 years

(Cl. D26—10)

Figure 1 is a perspective view of an electrical terminal assembly, showing our new design;

Figure 2 is a side elevation thereof; and

Figure 3 is a section view taken in the direction of arrows 3—3 of Figure 2.

The essential features of our design reside in the portions shown in full lines.

We claim:

The ornamental design for an electrical terminal assembly, substantially as shown and described.
